C. A. HOSIER

VENTILATOR FOR FARM BUILDINGS

Filed May 2, 1927

UNITED STATES PATENT OFFICE.

CLARENCE A. HOSIER, OF ROLFE, IOWA.

VENTILATOR FOR FARM BUILDINGS.

Application filed May 2, 1927. Serial No. 188,181.

My invention relates to ventilators of the kind used for controlling the supply of fresh air for farm buildings.

More particularly, it is my object to provide such a ventilator of the type having openings covered by fabric, such for example as muslin, whereby a proper volume of fresh air may be supplied to the building with a minimum of variation in draft due to wind.

Another object is to provide such a ventilator having movable parts for controlling the flow of air.

With these and other objects in view, my invention consists in the construction, arrangement and combination of the various parts of my ventilator for farm buildings whereby the objects contemplated are attained, as hereinafter more fully set forth, pointed out in my claims, and illustrated in the accompanying drawings, in which:

Figure 1 is a perspective view of a ventilator embodying my invention installed on a barn roof.

Figure 2 is a vertical, central, sectional view through the ventilator.

Figure 3 is a horizontal, sectional view taken on the line 3—3 of Figure 2; and

Figure 4 is a sectional view taken on the line 4—4 of Figure 2.

In the drawings herewith, I have used the reference numeral 10 to indicate generally the roof of a barn or other farm building.

My improved ventilator has a suitable base 12, shaped to fit the roof and provided with the ordinary flashing 14.

Extending upwardly from the base 12 is the ventilator body, which is rectangular in shape, and has the four side walls indicated generally at A.

Each side wall has the greater part of its central portion cut out to form preferably a square opening 16 of substantially the same area as the opening at the bottom of the ventilator body A.

The opening in the barn roof indicated at 18 is of substantially the same area as that of each of the holes 16, and should be approximately one square foot for each six hundred cubic feet of air space in the building.

The walls A extend upwardly substantially above the openings 16 as clearly illustrated in Figure 2.

On the inside of one wall A are supporting clips or the like 20, located above the open-

ings 16, and the opposite wall has near its 55 side edges the spring clips 22.

I provide a rectangular frame 24 adapted to have one edge rest on the spring clips 22. The walls A have an inwardly extending flange 26 just above the frame 24. The frame 24 is covered with fabric 28, such as muslin as illustrated in Figure 2.

A fabric cover 30 is extended around the body A of the ventilator and is of sufficient size to fully cover the openings 16. It may be 65 fastened in place in any suitable way.

The walls A have their upper corners inclined as at 32. Seated on the inclined edges of the walls A is the roof or top B of the ventilator, which may have any shape fanciful or otherwise suitable for the purpose. As shown, the roof is in the form of four gables 34.

Above each wall A and extended to the peak of the appropriate roof gable 34 is a 75 triangular shaped opening 36, preferably covered by a screen 38 to keep out sparrows and so on.

In the outer part of each gable, spaced outwardly from the wall A and opening 36 is a 80 triangular baffle plate 40, extending downwardly below the upper edge of the adjacent roof A. This leaves a narrow space 42 between each baffle plate 40 and the upper part of the adjacent wall A and the screen 38 85 thereabove.

In the lower part of the body A of the ventilator is a closure device, which may be of any suitable kind. As shown, it consists of two wings 44 and 46 pivoted at their ends, 90 preferably in the opposite walls A, by means of shafts 48, secured to the wings 44 and journaled in the opposite walls A.

Secured to each of the wings 44 and 46 near one end thereof adjacent to their meeting edges are ears 50. Pivoted to each ear 50 is a link 52, which extends upwardly. The upper ends of the links 52 are pivoted as at 54 to a controlling rod 60, which hangs downwardly as shown in Figure 2.

Between the controlling rod 60 and the links 52 is a spacer washer 62.

The rod 60 slides through a guide clip 64 mounted on the inner side of one of the walls A at its lower part.

Inside the base 12 is a cross member 66, which serves as a base and also as a support for another guide clip 68. The rod 60 slides

between the guide clip 68 and the base 66. The guide clip 68 is slidably mounted on small posts 70 supported by the guide 66. On the posts 70 are mounted coil springs 72 for yieldingly holding the guide clip 68 against the rod 60 for thus frictionally holding the rod 60 and the wings 44 and 46 in any adjusted position.

In the practical use of my improved ventilator, it is installed for instance in the manner 10 shown and explained herein.

The amount of ventilation desired may be controlled very largely by regulating the positions of the wings 44 and 46.

I find that by using the fabric covering 30 and the fabric 28, adequate ventilation is secured without those variations and sudden drafts, which are likely to occur, when there is a direct unimpeded flow of air through the ventilator.

20 It is hard to control the ordinary ventilator without the requirement of too much and too constant attention, when there is a wind blowing.

A ventilator of this kind affords much more 25 nearly a uniform supply of fresh air regardless of variations in wind velocity.

In the summer when a direct air flow unimpeded by the fabric is desired, the wings 44 and 46 may be opened, and by pressing the 30 clips 22 closely against the adjacent wall A, the frame 24 may be removed for allowing free flow through the passages 42, the openings 36 and then down through the ventilator body.

35 In windy or more particularly in cold weather, the frame 24 may be replaced.

It will, of course, be understood that my 40 ventilator may be made of any suitable material and that the shape and particularly the shape of the roof may be changed as may be desired.

The ventilator is intended to be made in various sizes for different buildings.

45 It is my intention to cover by the claims of the patent to be issued upon my application any modifications of structure, shape or ar-

angement of the parts of my ventilator and any use of mechanical equivalents, which may be reasonably included within their scope.

I claim as my invention:

50 1. A ventilator comprising a hollow body having openings in its side walls and fabric covers therefor, a fabric partition at the top of said body, and a roof for said ventilator, said ventilator being provided with openings at the upper part of its side walls between said walls and the roof, said roof having baffle plates extending from its upper portion on its under side downwardly to the tops of said first 55 openings in the side walls.

55 2. A ventilator comprising a hollow body having openings in its side walls and fabric covers therefor, a fabric partition at the top of said body, a roof for said ventilator, said ventilator being provided with openings at the upper part of its side walls between said walls and the roof, said roof having baffle plates extending from its upper portion on its under side downwardly to the tops of said first 60 openings in the side walls, and an adjustable closure device in the lower part of the ventilator body.

65 3. A ventilator comprising a hollow body having openings in its side walls and fabric covers therefor, a fabric partition in said body above said openings and a roof for said ventilator, said side walls being provided with openings above said partition underneath said roof for allowing the entrance of air before passing through said partition.

70 4. A ventilator comprising a hollow body having openings in its side walls and fabric covers therefor, a fabric partition in said body supported above said openings on a removable frame and a roof for said ventilator, said side walls being provided with openings between said first mentioned openings and the roof for receiving air before it passes through said partition.

75 Des Moines, Iowa, April 13, 1927.

CLARENCE A. HOSIER.
